UNITED STATES PATENT OFFICE.

WILLIAM C. JOHNSON, OF BETHEL, CONNECTICUT, ASSIGNOR TO THE CLARK BOX COMPANY, OF DANBURY, CONNECTICUT, A CORPORATION OF CONNECTICUT.

METHOD OF AND MACHINE FOR CURLING HAT STAYS.

Application filed July 19, 1927. Serial No. 206,821.

Men's and boys' hats are stacked by manufacturers in cardboard boxes for storing and transportation to dealers, the lowest hat of the stack being set into a cardboard stay 5 with its brim resting upon and supported by the rim of the stay. The upper edges of the stays are bent over to form widened bearings for the hat brims to rest upon.

This invention relates to a process of and 10 machine for curling the upper edges of hat stays.

The object of the invention is to provide a method and machine by which large 15 smooth curls, termed balloon curls, may be simply, inexpensively and rapidly produced around the upper edges of cardboard hat stays, whereby rubbing friction of the supporting rims of the stays and the consequent danger of chafing the hat brims, which 20 would mar the hats and reduce their value, incident to handling and transportation, will be practically eliminated.

This object is attained by providing a machine with frustro-conical rolls and a curler 25 to which the stays may be presented by an operative and the edges of the cardboard first stretched to obtain the necessary increase in diameter, and then, without removing the stays or interrupting the operation 30 the stretched edges may be curved into wide smooth curls which will support hats without chafing the brims.

In the accompanying drawings Fig. 1 shows a side elevation of a machine that 35 embodies the invention and by which the process may be practiced, with the frame cut in section. Fig. 2 illustrates on larger scale the first or stretching action of the rolls on the cardboard stay. Fig. 3 illustrates the 40 following or curling action. Fig. 4 is a plan of the curler which is used. Fig. 5 is a front elevation showing the relation of the curler to the conical rolls. Fig. 6 on reduced scale shows a section of a stay before 45 it is operated upon according to this invention. Fig. 7 shows a section of a stay in its completed condition.

The machine which is illustrated for carrying out the process has a frame or casing 50 1 desirably cast to shape with means for supporting it upon a bench or table. Supported by bearing sleeves 2 and 3 fixed in the lower part of the frame is a shaft 4 that at its rear end has a driving pulley 5. Se- 55 cured to the front end of this shaft is a

roll 6 that has an inwardly tapering peripheral surface 7 and a cylindrical peripheral surface 8 of smaller diameter than and at the rear of the tapering surface of the roll. Fastened to the shaft 4 is a gear 9 meshing with which is a gear 10 fastened to a shaft 11 on the front end of which is a conical roll 12. This roll 12 has an outwardly tapering peripheral surface 13 and a narrow cylindrical peripheral surface 14 on its inner side. The shaft 11 is fitted in a bearing sleeve 15 that is held in a block 16 which is pivoted in an opening in the rear wall of the frame by trunnions 17. The front end of the upper shaft is fitted in a bearing 60 sleeve 18 which is held by a block 19 that is free to move up and down in an opening in the front wall of the frame. A spring 20 is arranged between the block and the frame to normally lift this end of the shaft 11 65 and hold the roll 13 raised. A plunger 21 is placed in the top of the frame so as to engage the block 19. A lever 22 pivoted on the stud 23 fastened on top of the frame is arranged to press the plunger down and hold the periphery of the upper roll adjacent to the periphery of the lower roll when the machine is being used. 70

Fastened to the frame with its opening in line with and close to the adjacent peripheral surfaces of the upper and lower rolls when they are in operative relation, is a funnel shaped curler 24. The operative surfaces in the interior of this curler are curved and taper practically in all directions from 75 the large entrance end 25 to the small exit end 26, and there is an opening from the front toward this curved operating wall. 80

In carrying out the process with a machine of this character power is applied to 85 the pulley and through the gears and shafts both rolls are rotated. The upper edge of the stay blank which is a conical tube of cardboard is dipped into warm water which 90 softens it to an extent, and this wet edge is inserted by the operative a short distance 95 between the rolls, and the upper roll, by means of the lever is brought down so as to compress the wet edge of the stay between the rolls. The conical rolls rotate rapidly 100 and the stay rolls around with them. The first few rotations of the rolls stretches the edge of the paper so that this edge assumes substantially the relation to the body of the stay that is indicated at 27 in Fig. 2. When 105 110

the edge of the stay has become stretched in this manner the operative by pressure on the bottom of the stay forces the stay further and further in between the rolls, and 5 as this takes place the wet edge is caused to follow around the inner curved wall of the curler, and be curved over and under the peripheral edge of the cylindrical section 14 of the upper roll 12, which results in forming 10 the wide curl on the edge, as indicated in Fig. 3. When the curl is completed the upper roll is allowed to rise and the stay is removed. The action of the rolls is continuous, they, as the stays are presented by 15 the operative, first stretch the edges and then as the operative advances the stays between the rolls the wet stretched edges are curled. By the practice of this method and with such a machine as described large smooth curls 20 can be very rapidly produced on the edges of the stays.

The invention claimed is:—

1. A machine for curling hat stays comprising a frame, a shaft rotatably supported 25 in bearings fixed in the frame and carrying a gear and a tapering roll, a shaft rotatably supported in bearings pivoted in the frame and carrying a gear and a tapering roll, said gears intermeshing and said rolls tapering 30 reversely, means for swinging the pivotally supported shaft and moving the roll which it carries toward and from the other roll, and a curler attached to the frame and located to curve the edge of a stay back of the 35 opening between the peripheries of the rolls.

2. A machine for curling hat stays comprising a frame, a shaft carrying a tapering roll, rotatably supported in bearings fixed in the frame, a shaft carrying a tapering roll,

rotatably supported in bearings pivoted in 40 the frame, said rolls tapering reversely, means for swinging the pivotally supported roll toward and from the other roll, and a curler attached to the frame and adapted to curve the edge of a stay back of the opening 45 between the peripheries of the rolls.

3. A machine for curling hat stays having a roll with an inwardly tapering periphery and a cylindrical periphery inside thereof, a roll with an outwardly tapering periphery 50 and a cylindrical periphery inside thereof, means for rotating said rolls, means for separating and bringing together said rolls, and a curler attached to the frame and arranged to curve the edge of a stay adjacent 55 to the opening between said rolls.

4. The method of forming a curl on the edge of a cardboard hat stay which comprises immersing the edge of the stay in warm water, stretching the wet edge of the 60 stay by inserting it between rapidly rotating conical rolls, and then forcing the stretched edge further in between the same rolls and into contact with the curved tapering wall of a curler and causing the 65 stretched edge to be formed over and turned down by the cooperative action of the wall of the curler and rotative action of the rolls.

5. The method of forming a curl on the 70 edge of a cardboard hat stay which comprises wetting the edge of the stay, stretching the wet edge of the stay by rotating tapering rolls, and then curling said stretched edge by the cooperative action of 75 the wall of a curler and rotative action of the rolls.

WILLIAM C. JOHNSON.
